UNITED STATES PATENT OFFICE.

WILLIAM A. HOENEMAN, OF CLIFTON, ASSIGNOR OF ONE-HALF TO FRANKLIN P. HOENEMAN, OF NEW YORK, N. Y.

DESIGN FOR A CLOCK-CASE.

SPECIFICATION forming part of Design No. 23,929, dated January 1, 1895.

Application filed November 8, 1894. Serial No. 528,351. Term of patent 7 years.

To all whom it may concern:

Be it known that I, WILLIAM A. HOENEMAN, a citizen of the United States, residing at Clifton, in the county of Richmond and State of 5 New York, have invented a new Design for Clock-Cases, of which the following is a specification.

My design comprises the clock case, the legs, and the horizontal cylinder.

10 The accompanying drawing illustrates in perspective my new design.

Thus, referring to the drawing, A, represents a clock case having a clock face and hands on one side, and above the same is a 15 bell-shaped portion B, with a ring C, projecting above the bell-shaped portion. Extending outwardly and downwardly from the clock

case are the legs D, and arranged between the legs is a horizontal cylinder E. A narrow strip F, crosses two of the legs in front of the 20 cylinder.

The essential features of my design comprise the clock case, the legs, and the horizontal cylinder.

What I claim is—

25 The design for a clock case, substantially as shown and described.

In testimony whereof I have signed my name to this specification in the presence of two subscribing witnesses.

WILLIAM A. HOENEMAN.

Witnesses:

F. P. HOENEMAN,
HERMAN BROHMER.
